UNITED STATES PATENT OFFICE

2,347,487

ROTARY DRIER

Henry Kirchmann, Jr., San Francisco, Calif., assignor of one-half to Alfred N. Warburton, Oakland, Calif.

Application July 13, 1940, Serial No. 345,382

3 Claims. (Cl. 34—142)

My invention relates to means for drying various commodities, particularly finely divided products, and is concerned especially with means for facilitating the rapid and economical drying of such materials.

It is an object of my invention to provide a generally improved rotary drier.

The foregoing and other objects are attained in the embodiment of the invention illustrated in the drawing, in which—

Fig. 1 is a cross-section, on a vertical longitudinal plane, through a rotary drier in accordance with my invention;

Fig. 2 is a cross-section the plane of which is indicated by the line 2—2 of Fig. 1; and

Fig. 3 is a cross-section similar to Fig. 2 but showing a modified form of flue arrangement.

In its preferred form, the rotary drier of my invention includes an inner drum and an outer drum which are rotated in unison during the time that material to be dried passes therethrough, such material being under the control of an inlet valve at one end of the outer drum and a discharge valve at the other end of the outer drum, the inner drum being in a generally closed circuit including a furnace disposed adjacent one end of the inner drum and having a conduit providing means for returning exhaust fluid from the inner drum to the furnace, there being a discharge opening for release of circulated fluid as well as an inlet opening for the admission of atmospheric air to the furnace.

In its preferred form, my rotary drier is mounted on a suitable foundation 6, such as a floor, from which are upstanding pedestals 7 and 8. The pedestals are of different heights and act as supports for rollers 9 engaging circumferential rings 11 encompassing an outer drum 12. This outer drum is circular in cross-sectional contour, preferably, and adjacent one of the bands 11 carries a ring gear 13 meshing with a pinion 14 extending to any suitable source (not shown) of rotary driving energy. One end of the outer drum 12 is received within a header or jacket 16 making close running fit with the drum so that the drum can rotate with respect thereto with only a minimum of leakage. The jacket 16 is provided with an inlet valve 17 which comprises a generally circular-cylindrical body with a vaned rotor 18 therein driven by a chain 19 from a feed conveyor 21. This conveyor is propelled in any suitable fashion and brings the material to be dried and discharges such material into the valve 17. The material is then passed through the valve with the admission of only

small amounts of outer air and without permitting the free escape of the contents of the outer drum. The material passes through the jacket 16 into the outer drum 12 and, as such drum rotates, the material gradually gravitates toward the opposite end thereof because the drum is disposed with its central axis inclined to the horizontal. Having traversed the entire length of the outer drum 12, the material enters a discharge jacket 22 which is stationary and which serves as a convenient member for the junction of a suction outlet 23 so that a subatmospheric pressure can be maintained within the outer drum 12. The jacket 22 is provided with an outlet valve 24 having vanes 26 therein which are suitably driven through a chain 27 by a discharge conveyor 28, so that material released from the outer drum passes through the valve 24 without admitting surplus exterior air and without permitting the escape of an unusual quantity of material, and is carried away on the belt 28 to any suitable point.

In order to increase the temperature within the outer drum during the traverse of material therethrough, to facilitate the drying operation, I dispose a furnace 31 at one end of the mechanism, which is supported on the floor 6. A suitable burner 33 supplies fuel, and a damper 34 admits a regulated quantity of atmospheric air to support combustion. The products of combustion pass from the furnace 31 and through an expansion section 36 into an inner drum 37. The inner drum includes a cylindrical envelope extending between a pair of heads 38 and 39 disposed coaxially within the outer drum 12, which heads are joined by a plurality of flues 41. These flues either are composed of pipes having a circular-cylindrical cross-section as shown in Fig. 2 or, preferably, as shown in Fig. 3 are constituted by tubes 41' having a geometrical cross-section approximating a lozenge, so that a large amount of flat surface is presented for the momentary deposit of material to be dried thereupon. The inner drum 37 is supported within the outer drum by diametrical struts 43 extending therebetween, so that as the outer drum 12 rotates, the inner one rotates in unison therewith. The inner drum 37, beyond the header 39, that is, at its opposite end, continues with the reduced portion 44 communicating with the inlet 46 of an exhaust blower 47 driven from any suitable source 48 and effective to withdraw the gaseous contents of the inner drum and discharge them through a conduit 49 which extends back to the inlet 51 of the furnace adjacent the air damper 34. At a suitable

point in its length the conduit 49 has a discharge outlet 52 controlled by a manually adjustable damper 53, so that some portion of the returned gases can be discharged while atmospheric air is freely admissible through the dampers 34 to be admixed with the returned warm gases 51 for recirculation.

In the general operation of this structure, as the furnace functions and the blower 47 assists in drawing warm gases through the inner drum—that is, through the flues 41 or 41' included in such drum—and continues to recirculate such warm gases, the material passing between the outer drum and the inner drum is placed in contact with the hot surfaces and is deprived of its moisture, the effect being augmented by a tumbling action of the material produced not only by the various flues 41 or especially 41' but also by a plurality of longitudinal plates 54 which extend lengthwise of the outer drum and act to lift and then drop material progressing therethrough.

I claim:

1. A rotary drier comprising a rotatable drum, longitudinally extending heating flues mounted to rotate with said drum, a source of heat supply

connected to said flues, a feed conveyor, a material feeding valve disposed to discharge material from said feed conveyor into one end of said drum, means for driving said feed conveyor and said feeding valve in unison, a discharge valve and a conveyor receiving material from said discharge valve.

2. A rotary drier comprising a rotatable drum, longitudinally extending heating flues mounted to rotate with said drum, a source of heat supply connected to said flues, a feed conveyor, a material feeding valve disposed to discharge material from said feed conveyor into one end of said drum, means for driving said feed conveyor and said feeding valve in unison, a discharge valve, a discharge conveyor and means for driving said discharge valve and discharge conveyor in unison.

3. A rotary drier comprising a rotatable drum, a source of heat supply connected to said drum, a feed conveyor, a material feeding valve disposed to discharge material from said conveyor into one end of said drum, means for driving said feed conveyor and feeding valve in unison and a material discharge valve at the other end of said drum.

HENRY KIRCHMANN, JR.
